UNITED STATES PATENT OFFICE

CLARENCE S. WICKES, OF MERCHANTVILLE, NEW JERSEY, ASSIGNOR TO VICTOR
TALKING MACHINE COMPANY, A CORPORATION OF NEW JERSEY

STYLUS-HOLDING MEANS

Application filed September 28, 1926. Serial No. 138,222.

This invention relates to sound-recording and sound-reproducing machines, and more particularly to means for maintaining the stylus of sound-reproducing or recording instrumentalities in operative position.

It has heretofore been customary to provide a screw having a knurled head for retaining the stylus in operative relation with the stylus bar of a sound box. The weight of the knurled head of the retaining screw appreciably adds to the mass that must be vibrated and the inertia of this mass tends to reduce the perfection of the sound reproduced or recorded by the device.

It is an object of this invention to reduce the mass that must be vibrated by the vibratory element of sound-recording or reproducing instrumentalities, whereby inertia effects are materially reduced, and a more perfect reproduction and/or recording of sound is secured.

Another object of this invention is to provide novel means of relatively small mass for maintaining the stylus in operative relation with the vibrating element of the recording or reproducing instrumentalities.

Other objects include the provision of novel non-vibratory means for actuating the stylus retaining means whereby the stylus in use may be readily replaced by a new stylus or needle.

The invention is capable of receiving a variety of mechanical expressions, and it will therefore be understood that the embodiment shown on the accompanying drawings is for purposes of illustration only and that said drawings are not to be construed as defining the limits of the invention, reference being had to the appended claims for that purpose.

Referring to said drawings, wherein the same reference characters refer to like parts in the two figures—

Fig. 1 is a front elevation of a sound-box embodying the present invention; and

Fig. 2 is an enlarged, detail, sectional view taken on the line 2—2 of Fig. 1.

In the form shown, the invention is illustrated as embodied in a sound-box of the mechanical type but said invention is equally applicable to sound-reproducing and record-

ing devices of the electrical or electromagnetic types. The sound-box illustrated comprises a casing 3 of any suitable size, shape, material and construction, and which may be either a recording or a reproducing sound-box, and a diaphragm, not shown, of any suitable size, shape, material and construction, mounted in any suitable way. Operatively connected to the diaphragm is a stylus bar 4 having on the lower end thereof a socket portion 5 that may be cylindrical in shape, and is provided interiorly, if desired, with a triangularly or other suitably formed socket 6 for receiving any suitable type of stylus 7.

The stylus bar 4, 5 is oscillatably mounted on the casing in any suitable manner but preferably in a manner described and claimed in the copending application of C. D. Haigis and L. Y. Squibb, Serial No. 115,545, filed June 12, 1926, wherein the casing is provided with a pair of ring-like projections 8 which constitute retaining means for a flexible stylus bar mounting. It is to be expressly understood, however, that the particular mounting of the stylus bar constitutes no part 75 of the present invention.

In the form shown, one of the ring-like projections 8 is provided with a portion 9 having a plane face (Fig. 2) which is inclined with respect to the lateral face of casing 3. A member 10, having the form of a socket wrench, extends through an opening 11 in lug 9. The outer end of member 10 is provided with a knurled head 10^a, while the inner end thereof is formed to constitute a 85 socket member 10^b. Interposed between the inclined face of portion 9 and the lower surface of knurled head 10^a, is a suitable resilient member 12 which, in the form shown, is a coil spring surrounding the stem of wrench member 10. Threaded through the wall of stylus bar socket portion 5, and adapted to extend into the socket 6, is a stylus retaining member 13 which is provided on its outer end with a headed portion 13^a adapted to be 95 engaged by the inner or socket end of the wrench member 10.

If it is desired to remove stylus 7 from engagement with stylus bar 4, 5, the actuating member 10 is moved inwardly, against 100

the tension of spring 12, until the socket portion 10^b engages the headed portion 13^a of retaining member 13, whereupon 10 is rotated in a counterclockwise direction by 5 means of the knurled head 10^a and retaining member 13 is threaded out of engagement with the stylus, whereupon the latter may be removed from the socket 6. A fresh stylus is secured in position by rotating retaining member 13, by means of the socket wrench 10, in a clockwise direction. When the wrench member 10 is released, coil spring 12 returns said wrench to the normal position, indicated in full lines in Fig. 2, out of engagement with the stylus retaining member, and the stylus bar. The weight usually resulting from the use of a knurl-headed adjusting member on the lower end of the stylus bar is thus eliminated, whereby the mass to 20 be vibrated is materially reduced.

It will therefore be perceived that a novel stylus holder has been provided which is simple in construction and operation, and which enables the vibratory mass to be materially reduced. Novel means are provided for mounting the actuating device for the stylus retaining member, whereby said actuating device is normally disengaged and automatically from the retaining member and 30 does not vibrate therewith.

While the invention has been shown and described as embodied in a sound-reproducing or recording device employing a diaphragm, it is to be expressly understood that 35 the invention is not restricted thereto as the invention is of equal applicability to sound-reproducing or recording devices wherein, for example, the diaphragm is replaced by an electromagnetic vibratory element. Reference will therefore be had to the claims here-to appended for a definition of the limits of the invention.

What is claimed is:—

1. In a sound-box, the combination with 45 the sound-box casing, of a stylus bar carried by the casing, a rotatable stylus retaining member carried by the bar, a wrench operatively associated with said member to release or engage the stylus, and means normally retaining said wrench out of engagement with the retaining member.

2. In a sound box, in combination with the casing thereof, a stylus bar mounted on said casing, a stylus retaining screw threaded 55 transversely in said bar, and a socket wrench slidably mounted on said casing and longitudinally displaceable to engage the outer end of said screw, said wrench being normally out of engagement with said screw.

60 3. In a sound box, in combination with the casing thereof, a stylus bar mounted on said casing, a stylus retaining screw threaded transversely in said bar, a socket wrench 65 slidably mounted on said casing and longitudinally displaceable to engage the outer

end of said screw, and resilient means normally maintaining said socket wrench out of engagement with said screw.

4. In a sound box, in combination with the casing thereof, a stylus bar mounted on said casing, a stylus retaining screw threaded 70 transversely in said bar, a socket wrench mounted on said casing in alinement with said screw, said wrench being longitudinally displaceable to engage said screw, and resilient means normally holding said wrench out of engagement with said screw. 75

5. In a sound box, in combination with the casing thereof, a stylus bar mounted on said casing, a stylus retaining screw threaded 80 transversely in said bar and having a squared outer end, a longitudinally displaceable socket wrench mounted on said casing in alinement with said screw and having its socket portion shaped to receive said squared end, 85 and means normally maintaining said socket wrench out of engagement with said screw.

6. In a sound box, in combination with the casing thereof, a stylus bar mounted on said casing, a stylus retaining screw threaded 90 transversely in said bar and having a squared outer end, a longitudinally displaceable socket wrench mounted on said casing in alinement with said screw and having its socket portion shaped to receive said squared end, 95 resilient means normally holding said wrench in normal disengaged position, and a head formed in said wrench for displacing the same whereby it is coupled with said screw for rotation to release or engage the stylus. 100

7. A sound box comprising a casing, a stylus bar mounted on the casing, a socket wrench slidably mounted on the casing, resilient means interposed between the wrench and said casing, and stylus retaining means carried by said bar, and adapted to be engaged by said wrench, said resilient means being adapted to normally maintain the socket wrench out of engagement with said stylus retaining means. 105

8. In a device of the class described wherein in a stylus bar, provided with a stylus retaining member, is mounted for vibratory movement relatively to a casing, an actuating device slidably mounted on said casing to actuate the stylus retaining member to release or engage the stylus, the actuating device being provided at its outer end with a manipulating portion and at its inner end with a socket adapted to receive a portion of the stylus retaining member, and said device being normally out of engagement with said retaining member. 115

9. In a device of the class described wherein in a stylus bar, provided with a stylus retaining member, is mounted for vibratory movement relatively to a casing, an actuating device movably mounted on said casing to actuate the stylus retaining member to release or engage the stylus, the actuating de- 120 125 130

vice being provided at its outer end with a manipulating portion and at its inner end with a socket adapted to receive a portion of the stylus retaining member, and a spring positioned between said manipulating portion and said casing for normally maintaining the actuating device out of engagement with the retaining member.

5 In testimony whereof I have signed this
10 specification.
